UNITED STATES PATENT OFFICE.

ANDRÉ M. MERTZANOFF, OF BUFFALO, NEW YORK.

BOILER.

1,397,010.

Specification of Letters Patent. Patented Nov. 15, 1921.

Application filed March 6, 1917. Serial No. 152,574.

To all whom it may concern:

Be it known that I, ANDRÉ M. MERTZANOFF, a subject of the King of Greece, residing at Buffalo, Erie county, in the State of New York, have invented certain new and useful Improvements in Boilers, of which the following is a full, clear, and exact specification.

My invention relates to improvements in boilers, and has for its object to provide a boiler which will be efficient in operation with respect to the heating of the water and to the consumption of fuel.

A further object of the invention is to provide a boiler having a flue or flues of such construction that the tension of the gases passing therethrough will remain constant throughout the length thereof.

A further object of the invention is to provide a boiler having a flue or flues so constructed that the draft therethrough will be maintained uniform for all positions of the draft regulating dampers whereby a steady operation of the boiler is insured.

A further object of the invention is to provide a boiler having a flue or flues so formed that the transverse cross-sectional area thereof will progressively and uniformly decrease throughout the length thereof.

A further object of the invention is to provide a boiler having a flue or flues so formed that the transverse cross-sectional area thereof will decrease as the temperature of the gases decreases.

Other objects will in part be obvious and in part be pointed out hereinafter.

To the attainment of the aforesaid objects and ends my invention consists in the novel details of construction, and in the combination, connection and arrangement of parts hereinafter more fully described and then pointed out in the claims.

In the accompanying drawings showing an illustrative embodiment of the invention—

Figure 1 is a front elevational view of the boiler;

Fig. 2 is a part plan and part sectional view, the section being taken on the line 2—2 of Fig. 3, and

Fig. 3 is a sectional view taken on the line 3—3 of Fig. 2.

Boilers as ordinarily manufactured are designed to yield their best results at catalogue rating. This practice, however, has

been found to be most unsatisfactory and extravagant since it has been definitely ascertained that to design a boiler to yield its maximum efficiency at catalogue rating results in a sacrifice of heating efficiency when the boiler is operated at its normal rate or output, which, of course is that rate at which it operates during the greater part of the heating season.

The operation of a boiler is generally about as follows:—Early in the morning the boiler is coaled and then "forced" for a short period of about 40 to 50 minutes during which time the boiler is called upon to deliver its entire catalogue rated capacity. During the "forcing" period the boiler may be considered as subjected temporarily to an overload.

Late at night the boiler is checked to a point where it is capable only of maintaining the fuel in an incandescent or partly incandescent state and burns at a leisurely rate. At this time the output of the boiler is practically minimum, or approximately ten per cent. of the boiler's normal output. During the night period which approximately covers about eight hours, extending from 10 or 11 o'clock at night to 6 or 7 o'clock the following morning, the demand upon the boiler is at a minimum and the rate of combustion is, therefore, correspondingly low.

The period of approximately fifteen hours between the "forcing" period and the "night" period constituting about sixty-five per cent. of the total daily period of operation, is the period in which the operating conditions of the boiler are normal. During this intervening or normal period the rate of combustion remains substantially constant and unvarying.

The purpose of the applicant's invention is to provide a boiler which will yield the best heat return for the fuel consumed during this period when the boiler is operating under said normal conditions.

While for purposes of illustration the invention is shown in connection with a boiler of the sectional type, it is, of course, to be understood that it is not to be limited to this particular form of boiler as it is equally well adapted for use in connection with other types of boilers.

Referring to the drawing the boiler is shown as comprising a pair of hollow end sections 10, 10, and a plurality of hollow

intermediate sections consisting of two similar, oppositely disposed parts 11, 11. At their upper and lower portions the end sections 10, 10 and the parts 11, 11, of the intermediate sections are provided with registering openings 12 within which are arranged nipples 13, thereby providing for the free circulation of water throughout the boiler. The boiler is preferably inclosed within a casing 14 and is provided with a suitable automatic damper controlling device 15.

Each of the parts 11 of the intermediate sections extends substantially throughout the height of the boiler and is provided at its upper end with an inwardly extending portion 16 which overhangs the grate 17. Each of the parts 11 is provided with laterally extending peripheral fins 18 which engage corresponding fins of adjacent sections to form flues 19 there being no peripheral fin provided upon the inwardly projecting portions 16 which overhang the grate 17 whereby to permit of the passage of the gases from the combustion chamber into the flues. Openings 20 are provided in the lower portions of the sections forming longitudinal collecting flues through which the gases pass from the flues 19 to the pipe 21 which leads to the chimney.

30. The portion of each of the peripheral fins 18 which is adjacent the inner surface of each part 11 and which lies above the fuel bed terminates below the top of the boiler and is inclined inwardly and upwardly to an extent such that the effective transverse cross-sectional area of each of the flues will progressively and uniformly decrease from its inlet to its outlet in order that the tension of the gases passing through each flue will remain constant as the temperature of the gases decreases, thus insuring a steady rate of flow of the gases therethrough.

45. The desired results are best obtained by so forming the flue that at any point thereof from its inlet to its outlet, its transverse cross-sectional area will correspond to the formula $PV=RT$ in which formula—

P=the prevailing pressure in the flue,

V=the volume of the gas,

50. R=the constant for the gas, and

T=the absolute temperature of the gas.

Boilers constructed as herein described are quickly responsive and highly efficient as regards the consumption of fuel. By reason of 55 the peculiar formation of the flues the operation of the boiler is steady and the draft control and rate of combustion may be closely and accurately governed to meet the various requirements of the boiler. Furthermore by providing for a uniform tension of the gases passing through the flues the boiler will operate in accordance with the varying load requirements to which it may be subjected.

60. Having thus described my said invention,

what I claim and desire to secure by Letters Patent is:—

1. A sectional boiler comprising a plurality of members each embodying top and vertical side portions, said top and side portions forming a fuel receptacle and a combustion chamber; a longitudinal collecting flue communicating with the smoke outlet, and tapering flues in said side portions extending from said combustion chamber to said collecting flue, the cross sectional area of said flues at any point throughout their length being proportional under normal operating conditions of the boiler to the temperature of the gases at such point, substantially as specified.

2. A sectional boiler comprising a plurality of members each embodying a top and vertical side portions, said top and side portions forming a fuel receptacle, and a combustion chamber; a longitudinal collecting flue communicating with the smoke outlet, and tapering flues in said side portions extending from said combustion chamber to said collecting flue, the cross sectional area of said flues at any point through their length being of such size as to satisfy the equation— $PV=RT$ in which equation—

P=the pressure of the gases in the flue at said given point,

V=the volume of the gases at said given point,

R=a constant depending on the nature of the gases.

T=the absolute temperature of the gases at said given point, substantially as specified.

3. A sectional boiler comprising a plurality of members each embodying a pair of vertical side portions and inwardly extending portions adjoining their upper ends, said side and top portions forming a fuel receptacle and a combustion chamber, a longitudinal collecting flue communicating with the smoke outlet, and tapering flues in said side portions extending from said combustion chamber to said collecting flue; the cross-sectional area of said flues at any point throughout their length being of such size as to satisfy the equation— $PV=RT$ in which equation—

P=the pressure of the gases in the flue at said given point,

V=the volume of the gases at said given point,

R=a constant depending on the nature of the gases,

T=the absolute temperature of the gases at said given point, substantially as specified.

4. A sectional boiler comprising a plurality of members each embodying a pair of vertical side portions and parallel inwardly extending portions adjoining their upper ends and arranged in spaced relation to one

another, said side and inwardly extending portions forming a fuel receptacle and a combustion chamber; a longitudinal collecting flue communicating with the smoke outlet, and vertical downwardly tapering flues in said side portions extending from the upper portion of said combustion chamber to said collecting flue, the cross sectional area of said flues at any point throughout their length being proportional under normal operating conditions of the boiler to the temperature of the gases at such point, substantially as specified.

5. A sectional boiler comprising a plurality of inverted U-shaped members, forming a fuel receptacle and a combustion chamber, a common flue in the lower end of each of the vertical portions of said member, and tapering flues in said vertical portions communicating at their upper ends with the combustion chamber and at their lower constricted ends with their respective common flues, the cross-sectional area of said tapering flues at any point throughout their 20 length being proportional, under normal operating conditions of the boiler, to the temperature of the gases at such point, substantially as specified.

6. A sectional boiler comprising a plurality of inverted U-shaped members forming a fuel receptacle and a combustion chamber, laterally extending fins on said vertical portions coöperating with the registering fins of adjoining members and forming downwardly tapering vertical flues therebetween communicating at their entrance portions with said combustion chamber and at their exit portions with a common flue leading to the smoke outlet, the cross sectional area of 35 said flues at any point throughout their length being proportional under normal operating conditions of the boiler to the temperature of the gases at such point, substantially as specified.

40 7. A sectional boiler comprising a plurality of inverted U-shaped members each having relatively narrow transverse intermediate portions, the inner opposing walls of

said members forming a fuel receptacle and a combustion chamber therebetween; longitudinal flues in the bases of the vertical portions of said U-shaped members communicating with the smoke outlet, and downwardly tapering flues in said vertical portions extending severally from said combustion chamber to said longitudinal flues, the cross sectional area of said flues at any point throughout their length being proportional under normal operating conditions of the boiler to the temperature of the gases at 60 such point, substantially as specified.

8. A sectional boiler comprising a plurality of inverted U-shaped members, each composed of two conforming halves forming intermediate the same a combustion chamber 65 and a fuel receptacle, registering fins upon the outer edges of said members; each of said members having a relatively narrow tapering intermediate portion terminating in a broad lower end, registering openings in 70 said lower ends forming a longitudinal collecting flue leading to the smoke outlet, registering fins along the inner edges of said narrow tapering intermediate portion and said lower ends, forming the walls of said 75 fuel receptacle and said combustion chamber; said ribs in combination with the registering ribs upon the outer edges of said members jointly forming a plurality of downwardly tapering flues extending from 80 said combustion chamber to said longitudinal collecting flue, the cross sectional area of said flues at any point throughout their length being proportional under normal operating conditions of the boiler to the temperature of the gases at such point, substantially as specified.

Signed at the city of New York, in the county and State of New York, this 11th day of November, one thousand nine hundred and sixteen.

ANDRÉ M. MERTZANOFF.
